UNITED STATES PATENT OFFICE

91,705

DESIGN FOR A CARPET SWEEPER

Norman W. Cummins, Louisville, Ky., assignor to Adler Manufacturing Co., Inc., Louisville, Ky.

Application December 29, 1933, Serial No. 50,248

Term of patent 7 years

To all whom it may concern:

Be it known that I, NORMAN W. CUMMINS, a citizen of the United States, residing at Louisville, in the county of Jefferson and State of Kentucky, having invented a new, original, and ornamental Design for a Carpet Sweeper, of which the following is a specification, reference being had to the accompanying drawing, forming part thereof.

The figure is a perspective view of a carpet sweeper, showing my new design, a part of the handle being broken away for convenience of illustration.

I claim:

The ornamental design for a carpet sweeper as shown and described.

NORMAN W. CUMMINS.
